UNITED STATES PATENT OFFICE.

STEPHEN T. HISLEY, OF SYRACUSE, NEW YORK, ASSIGNOR TO THE SYRACUSE SPECIALTY MANUFACTURING COMPANY, OF SAME PLACE.

CLASP.

SPECIFICATION forming part of Letters Patent No. 451,482, dated May 5, 1891.

Application filed August 6, 1890. Serial No. 361,171. (No model.)

To all whom it may concern:

Be it known that I, STEPHEN T. HISLEY, of Syracuse, in the county of Onondaga, in the State of New York, have invented new and useful Improvements in Clasps, of which the following, taken in connection with the accompanying drawings, is a full, clear, and exact description.

This invention pertains to the class of 10 clasps which are chiefly used on arctic overshoes and in which a tongue is hinged to a frame or body-plate secured to one of the quarters of the shoe and interlocks with a slotted catch-plate attached to the other quarter or flap of the shoe; and the invention has 15 special reference to the species of clasps in which the tongue is formed with integral flat pivots which are inserted between the flexible ends of two spring-metal body-plates, 20 which latter are firmly united at the opposite end.

The object of the invention is to obviate the usual end extensions or projections of the body-plate in the same plane with said plate, 25 and thus avoid the liability of catching grass or strings or other analogous loose objects in the path of the wearer of the shoe provided with a clasp of the aforesaid class; and the object of the invention also is to guard more 30 effectually against the possibility of the tongue being drawn out from the end of its supporting-frame.

To these ends the invention consists in a novel and simple construction and combination 35 of the component parts of the clasp, as hereinafter fully described, and specifically set forth in the claim.

In the annexed drawings, Figures 1 and 2 are perspective views of clasps embodying 40 my invention. Fig. 3 is an edge view of the clasp shown in Fig. 2. Fig. 4 is a detached perspective view of the component parts of said clasp, and Fig. 5 is a plan view of the catch-plate.

45 C represents the slotted catch-plate, and t denotes the tongue, which interlocks with said plate in the usual and well-known manner in fastening the shoe or other article to which the clasp is applied. Said tongue is 50 curved in the usual manner and formed at one end with integral flat pivots c c, project-

ing laterally from opposite edges thereof, by which pivots it is connected to the front ends of the body-plates A and A' in the following manner: The plate A is formed at its rear end 55 with the cross-bar b and at the front end with the central opening o. Each of the portions of the plate at opposite sides of the opening o is formed with a notch, the transverse edge of which constitutes a laterally-extending 60 shoulder a, and the remainder of said portion of the plate is bent into the shape of a lip l, projecting at right angles from the plane of the plate. The other body-plate A' is placed upon the plate A and is formed at 65 one end with a cross-bar b', corresponding to the cross-bar b, and by a rivet passing through said cross-bars the two body-plates are firmly united at said or front end. The opposite end of the body-plate A' is formed with the 70 central opening o', and the portions at opposite sides of said opening are each formed with a recess d in the side adjacent to the plate A and terminated with a lip l', which projects across the front of the shoulder a of 75 the plate A. The two plates A A' are stamped out of sheet spring-steel, and are therefore adapted to be sprung apart at the ends, which are provided with lips l l'. The tongue t is connected to said body-plates by 80 inserting the pivots c c into the recesses d d of the plate A', which may be effected before riveting the opposite end of said plate to the plate A.

It will be observed that by the described 85 construction of the clasp the pivots of the tongue are retained between the body-plates by two sets of lips projecting in opposite directions from the said plates and across the front of the pivots, and thus each pivot is retained between the body-plates by a double lock, which effectually prevents the tongue from severing from the body-plates during 90 the operation of the clasp, in which operation the pintle pries the plates A A' apart at one 95 end, when the tongue is raised to engage or release the catch-plate C, and thus the tongue receives its required spring action.

Having described my invention, what I claim as new, and desire to secure by Letters 100 Patent, is—

The improved clasp consisting of the body-

plate A, formed at its front end with the opening *o* and terminating thereat with the transverse shoulders *aa* and lips *ll*, projecting at right angles from the plane of the plate in front of the said shoulders, the body-plate A', lying upon the plate A and secured to the rear end thereof and formed at the opposite end with the opening *o'* and terminated thereat with recesses *dd* and lips *ll'*, projecting across the front of the shoulders *aa*, and the tongue *t*, formed with the flat pivots

cc, projecting rigidly from opposite edges of the tongue and lying between the plates A A' immediately back of the lips *l* and *l'* of both plates, substantially as described and shown. 15

In testimony whereof I have hereunto signed my name this 31st day of July, 1890.

STEPHEN T. HISLEY. [L. S.]
